CAN OPENER

Walter E. Moore, St. Louis County, Mo., assignor
to Swing-A-Way Manufacturing Company, St.
Louis, Mo., a corporation of Missouri

Application November 3, 1951, Serial No. 17,260

Term of patent 14 years

(Cl. D44--29)

To all whom it may concern:

Be it known that I, Walter E. Moore, a citizen of the United States, residing in St. Louis County 21, Missouri, have invented a new, original, and ornamental Design for a Can Opener, of which the following is a specification, reference being had to the accompanying drawing, forming a part thereof.

Fig. 1 is a side elevational view of a can opener, embodying my new design;

Fig. 2 is a plan view thereof;

Fig. 3 is a side elevational view, showing the other side thereof; and

Fig. 4 is an end elevational view thereof, looking from left to right in Fig. 1.

The characteristic features of my novel design reside in the portions shown in full lines, the portions shown in broken lines being only for illustrative purposes.

I claim:

The ornamental design for a can opener, substantially as shown and described.

WALTER E. MOORE.
